UNITED STATES PATENT OFFICE.

WILLIAM H. PRIESS, OF BELMONT, MASSACHUSETTS, ASSIGNOR TO WIRELESS SPECIALTY APPARATUS COMPANY, OF BOSTON, MASSACHUSETTS, A CORPORATION OF NEW YORK.

ELECTRICAL CONDENSER AND METHOD OF MAKING THE SAME.

Application filed June 6, 1921. Serial No. 475,216.

This invention relates to electrical condensers and methods of making them. The invention is applicable to condensers of many types, among which are high potential condensers for use in radio communication, electric power circuits and the like.

An object of the invention is to provide a condenser adapted mechanically and electrically to preserve during service the high pressure initiated upon the condenser stack, (consisting of alternate sheets of foil and dielectric), during the process of manufacture, and consequent greatest practicable closeness of contact of surfaces of dielectric and conducting sheets, all under conditions of compactness and lightness, the construction being adapted for use not only in service but during the process of manufacturing.

Another object of the invention is to provide a compact, efficient condenser.

Another object of the invention is to provide a condenser in which the casing functions as a clamp, and which may be filled with an embedding material, preferably paraffin wax, while maintaining intimate contact between the sheets of foil and dielectric of the condenser stack.

Another object of the invention is to provide in a condenser of the above type means for exerting resilient spring pressure upon the stack, not only during the embedding or filling operation, but also in service.

Another object of the invention is to provide a condenser in which the cooling is a maximum.

Another object of the invention is to provide electrical protecting means between portions of the condenser at high potential difference.

Another object of the invention is to provide a condenser in which means is provided for allowing expansion of the wax or embedding material while maintaining a high degree of compactness of the embedding material around the high potential terminal and maintaining the sheets in intimate contact.

The present invention is an improvement upon the inventions disclosed in my co-pending applications Serial Number 332,421, filed October 22, 1919; S. N. 370,992, filed April 3, 1920; and S. N. 456,903, filed March 30, 1921.

The invention consists of the features described hereinafter and illustrated in the accompanying drawings, in which

Figure 1 is an elevation, partly in section, taken on the line 1—1 of Fig. 2, looking in the direction of the arrows;

Fig. 2 is a plan view with the upper plate 24 of Fig. 1 removed;

Fig. 3 is an elevation, partly in section, taken on the line 3—3 of Fig. 1, looking in the direction of the arrows; and

Fig. 4 is a detail perspective view of a spring pressure plate.

The present invention is especially adapted for maintaining the pressure on a stack 1, consisting of a number of sections 2 connected in series at 3 and provided with separators 4 interposed between the sections and projecting beyond the connections for the purpose of insulating the connections, which are at a difference of potential, from each other. Such a stack 1 consists preferably of alternate sheets of conductors and dielectric, preferably of some soft metal foil such as lead and a suitable dielectric such as mica. The stack is constructed and processed substantially as described in my co-pending application 456,903 and needs no further description here, the object of such processes being to remove air, moisture and insulating material from between the sheets of foil and dielectric and secure intimate contact between such foil and dielectric. The present invention has for its purpose the maintaining of such intimate contact not only during the embedding process, but in service by the means and methods herein described.

As an embodiment of the present invention, I have utilized as a clamping member a casing 5, preferably of some rigid material such as cast iron, or where weight is a factor a strong aluminum alloy, for example, 94% aluminum and 6% copper. This casing, in which the stack is located as illustrated, tapers upwardly and outwardly upon its inner surface 6, in order that the distance between the casing and the stack increases from the low potential end of the stack, which is the lower end, to the high potential end of the stack, which is the upper end. Hence it will be seen that the lower end of the casing may be very close to the lower end of the stack, while the up-

per end of the casing is spaced a greater but preferably minimum distance to secure the required insulation. The outer surface of the casing 5 is provided with a series of vertically-arranged ribs 7 therearound for increasing the heat-radiating surface of the condenser. Upon the bottom of the casing on the inside at opposite sides thereof are a pair of spaced shelves or ledges 8. A 10 large circular hole 9 is provided in the bottom of the casing, while the upper end of the casing is provided with an inwardly-projecting ledge 10 having a circular hole 11 therein, such ledge having slots there-through upon opposite sides to allow free circulation of air around the casing.

In order to maintain in service and during the wax-filling operation the sheets of the stack in intimate contact, I have provided means for maintaining resilient spring pressure upon the stack to allow slight variations in the length thereof, due to temperature changes, in the manner described in my co-pending applications 20 above referred to, although where a cheaper condenser is desired the spring may be omitted. As therein described, so here, this spring pressure means comprises a spring plate 12, as illustrated in Fig. 4, which is 25 substantially rectangular, has rounded edges and is bowed, when not under stress, as illustrated in Fig. 4. This spring 12 is constructed preferably of some strong springy material such as vanadium steel, 30 and is so designed that it will exert a pressure upon the stack of the order of a ton per square inch of the active surface of the stack when flattened out. In constructing the condenser, if a spring is used, the spring 35 12 is inserted within the casing 5, with its convex side uppermost and with its ends resting upon the shelves 8 at opposite sides of casing 5. Upon the spring plate 12 is placed a pressure plate 13 of some strong 40 rigid metal upon which the stack 1 rests, the lower section of the stack being electrically connected to the casing 1, which constitutes the low potential terminal, by 45 means of a conducting strip 14 (Fig. 1) which is connected to the lower section and clamped between the plates 12 and 13, which in turn are in electrical contact with 50 casing 6, by the clamping of plates 12, 13, to one another and to the inside wall of 55 the bottom of casing 6 by the stack-clamping arrangement now to be described. Mounted upon the opposite end of the stack is a pressure member 15 to which the uppermost section is electrically connected. 60 A terminal stud 16, projecting through hole 11 (Figs. 1 and 3), is threaded into the member 15, this stud constituting the high potential terminal of the stack. Around the stud 16 and resting upon the 65 member 15 is a fish paper washer 17, and

mounted around the terminal 16 and upon the washer 17 in the hole 11 (Figs. 1 and 3) is an insulating member 18, provided upon its upper surface with a plurality of concentric ribs or corrugations 19, as illustrated in Fig. 2, whereby the creepage distance between the high potential terminal 16 and the casing is increased. This insulating member 18 may consist of any suitable insulating material such as lavite, a suitable 70 grade of porcelain, bakelite, dilecto or quartz.

After the stack is assembled in the manner above described, a metal clamping collar 20 is placed around the insulating member 18, overlapping the rim of the same, and is clamped and secured to the top 10 of the casing 1 as a part thereof by means of a plurality of screws 21 arranged at the four corners of the clamping member (Fig. 2) 85 and extending through a gasket 22 (Figs. 1 and 3), to secure water-tightness. The screws 21 are all located equal distances from the terminal 16 and each exerts its share of pressure upon the stack. The 90 clamping member 20 is likewise made of some stiff, rigid metal such as cast iron or the previously-mentioned aluminum alloy. Threaded upon the threaded terminal 16 above insulating member 18 is a metal sleeve 95 23. Mounted upon the top of the sleeve 23 and around the terminal 16 is a metal member 24, in the form of a plate or disk or otherwise secured by nut 25, and upon the member 16 above the plate 24 is a nut 26, 100 which may be adjusted to secure a circuit conductor or lead thereto. After the condenser has been assembled and clamped together in the manner above described, it may be filled with a suitable embedding material such as oil or paraffin wax through the opening 9, this embedment being indicated at 27 (Figs. 1 and 3), care being taken to provide upon solidification of the embedment, (as in cases where solid embedment 105 of insulating material is used), a space 28 free of wax below the spring plate 12 to allow the expansion of the wax. After the wax has been placed in the casing the closure 29 may be soldered or otherwise secured 110 to close the opening 9, thus completing the condenser.

The metal member 24 has several functions. It not only constitutes a heat dissipating member for the terminal 16, which 115 is the heat-conducting member for the high potential end of the stack, (since the stack is in good thermo-conductivity with the pressure plate 15 in which terminal 16 is screwed), but member 24 is also of such an area that it provides a dust cover for the insulator 18, preventing aging and deterioration thereof. Furthermore, the periphery or edge of the high potential member 24 is 120 so spaced vertically above the clamping 125 member 20 that it will not interfere with the 130

member 20 that it constitutes a protective spark gap therewith, member 20 being connected via casing 5 with the low potential end of the stack 1. Member 24 as thus spaced as shown, closer to metal casing-part 20 than the distance thru insulator 18 from high to low potential conductors, serves to concentrate electrostatic lines across the safety spark gap and thereby prevent concentration of such lines in said insulator 18 which would be liable to be injuriously effected thereby. Member 24 therefore is a static shield for insulating bushing 18.

The process or method for building condensers of the type herein described is substantially as follows.

After the condenser stack has been treated in the manner described in my application 456,903 above referred to, it is ready to be placed within the casing 6. The spring plate 12 is first located upon the ledges 8, and upon the spring plate is placed the lower pressure plate 13,—or, in case no spring is used, the member 13 may be located directly 25 on ledges 8 (the conducting strip 14 then being clamped directly in contact with the inner wall of the bottom of casing 6),—and the stack is then positioned within the casing upon plate 13 with its lower terminal 14 clamped between the spring plate 12 and pressure member 13. The upper pressure member or terminal plate 15 is then located (as described, by screws 21) on top of the stack with the threaded rod, stud or terminal 30 16 projecting above it; the insulator 18 is then secured in position around stud 16 and on top of plate 15; and the whole is clamped preliminarily by means of the clamping member 20.

In the present embodiment of the invention, the condenser is preferably embedded or filled through the bottom through opening 9, the condenser being inverted for this purpose. It will be seen from an inspection 45 of Fig. 3 that there is a direct communication through the opening 9 past the bottom plate members 12 and 13 to points adjacent the top insulator 18 and upper pressure plate 15 to allow complete embedment of stack 1 save at its end faces.

After the parts are assembled as above described, the casing 6 is filled around the stack to heat the latter and the casing, with hot liquid insulating material such as 55 molten wax, preferably paraffin, and the casing is heated by the application of a Bunsen burner or the like to the outside of the casing 1. The wax is then emptied out of the casing, the casing placed under an arbor press while casing and stack are hot, and pressure applied to the metal member 15 and insulator 18 to compress the stack against the bottom wall of casing 6. The pressure of the arbor press has reached its 60 optimum value when, from inspection by

the operator, it is seen that the bottom spring plate 12 is perfectly flat. Under such conditions, the pressure over the opposite ends of the stack is of the order of 2,000 pounds per square inch of the active 70 surface. This pressure not only secures the intimate contact between the sheets of the stack, but the preliminary heating of the stack serves to soften any wax between its sheets, which, upon said subsequent pressure of the arbor press, is squeezed out, bringing the sheets of dielectric and foil in intimate contact. After the arbor press has secured the necessary pressure, and while it maintains such pressure the screws 80 21 are adjusted in member 15 and casing 6 to maintain this pressure.

The casing is then filled permanently with wax or insulating material through the bottom opening 9, the casing being inverted for this purpose. A false head first is secured around the normally lower end of the casing (opening 9) to provide a head of wax thereabove in the manner described in my application 456,903 above referred to and in patent to Macpherson No. 1,502,343 of 22 July 1924. Vacuum is then applied to the condenser casing 1 and its head, and while under vacuum the casing and head are filled molten wax is poured into the head 85 to fill both casing and head. The casing and head are then removed from the vacuum tank and the wax is cooled in a gradual manner from the bottom upwardly; that is, the bottom of the molten 90 wax (around insulator 18) is cooled, or heat is applied to the top of the molten wax, or both. The cooling may be by means of an air blast directed against the plate 24 and the surface of the clamp 20 and casing 6 adjacent to it. Hot irons may be kept in the head (around opening 9) to maintain the liquid molten therein. This method of cooling causes the high potential portions of the stack to cool and solidify first (around pressure plate 15 and insulator 18) producing a very solid mass about these points because the solidification occurs there while under pressure of all the molten wax above, 100 so that as the wax at the high potential 105 locations contracts upon progressive solidification, all otherwise resulting cracks or voids immediately are filled by gravitation of the molten wax just above, which in turn solidifies, etc.; the best effect of solidification 110 being at the lowest part of the molten mass which is at the high potential portions and usually becomes the upper part of the condenser in service. After cooling and solidification of the wax, the head is removed, and the wax cut off flush with the casing and gouged out between the bottom of the casing 1 and spring plate 12 to provide a space 28 free of wax to allow the 115 subsequent expansion of the wax 27, if dur-

120

125

130

ing service the condenser should heat. This space 28 is in the nature of a safety space to prevent strain upon the casing due to the expansion of the wax and the consequent expansion and loosening of the stack. The bottom closure 29 over opening 9 is then secured in position, and the condenser is completed. In some cases, the space 28 is omitted, as where oil is used as a filler or embedment. To provide adequately for expansion of any such embedment, the closure 29 may comprise a thin, flexible sheet of metal or diaphragm claimed in my patent 1,499,404 capable of expanding or of being distorted by the embedment in expanding, thus yielding sufficiently to prevent the loosening of the stack sheets through the distortion of the entire casing.

The condenser as above processed and constructed has the following advantages. The leakage distance between the terminal 16 and the adjacent portions of the casing on the outside of the condenser (as collar clamp 20) has been increased by the use of ribs or corrugations 19 of insulator 18. The disc 24, which is preferably of some high heat conductive material, as brass, provides substantial heat dissipation from the high potential portion of the stack through the pressure plate 15 and stud 16. The method of filling from the bottom claimed in my Patent 1,553,549 provides a thorough solid embedment, which is of uniform consistency or holosteric at the higher potential portions of the stack and especially at the high potential portions which are at the bottom of the head of molten wax during the bottom-filling step of the process. The wax volume in the stack has also been reduced to a minimum by the inclined inner wall of the casing thereby providing a maximum of heat conduction from the stack to the casing and a minimum volumetric expansion of the wax through temperature rise. The heat convection and heat radiating surfaces of the condenser have been increased by member 24 and by casing-corrugations 7 more than fifty per cent. over existing designs. Furthermore, the construction of the condenser is such as to maintain a permanent pressure of a high order of magnitude upon the opposite ends of the stack, maintaining the sheets of foil and dielectric in intimate contact and allowing for heat expansion of the stack by means of the spring 12. The possibility of wax cracks occurring in the condenser embedment has been reduced to a minimum, inasmuch as the high potential portions are the best and most solidly embedded portions. The gouging to remove the wax to provide the space 28, and cutting off of the head and surplus wax, as in the present invention, if it does produce cracks, produces them at points which are already at the casing potential, and there-

fore no breakdown from the stack to the casing can occur via any such cracks.

The high potential portions of the condenser are solidly embedded with wax, the wax being particularly solid against the 70 insulator 18, high potential pressure plate 15 and adjacent portions of the casing, thereby not only insuring against breakdown and creepage at these critical locations, but also providing a water-tight seal 75 around the high potential end of the stack through which moisture cannot pass by pumping action or the like.

The construction above described and disclosed in the drawings provides means 80 whereby the casing not only serves as a clamping member, but also provides means whereby the stack within the casing may be embedded while maintaining the pressure by means of the casing. The space 28 is located at the low potential end of the stack, and in case of expansion of the wax, this expansion is into this space without exerting pressure upon the clamping casing and consequent variation of the pressure of the 85 stack.

This invention adapts the entire condenser construction to high duty, both as to high potentials and high currents, the member 24 aiding materially in dissipating heat generated by heavy currents and also serving in the ways above described as an electrical protection in respect of high potentials. Also each and both of these aspects and their efficiency are materially assisted by the 90 heavy clamping of the stack in combination with the principal novel features of the rest of the structure.

It is to be understood that the invention is not limited to the embodiments and features specifically shown and described herein, but that such embodiments and features are subject to changes and modifications without any departure from the spirit 105 of the invention.

I claim:—

1. The combination with a high duty electrical condenser stack, of a metal casing therefor having its inner wall spaced from the lateral portion of said stack, at 110 least one end of the stack being held under high mechanical compression against a casing wall, the stack being in electrical and thermal connection via its said end with the metal casing as a low potential condenser terminal and a heat dissipator of large surface; said metal casing having two openings at opposite portions; a terminal extending from a high potential portion of 115 said stack to and thru one of said casing openings; an insulating member closing said opening and surrounding said high potential terminal; the high potential portion of the stack being located near said insulating member; a metal member located 120
- 125
- 130

BEST AVAILABLE COP

- outside the casing, supported by said high potential terminal, electrically and thermally connected thereto, and extending radially therefrom over said insulating member; 5 said metal member having a substantial heat dissipating surface to dissipate heat conducted by the high potential terminal from the stack thru said casing opening; the opposite casing opening being in communication with the interior space between the stack and the casing and permitting the introduction of molten insulating material into said space while the condenser is under said compression, to serve thereafter 10 to conduct heat from the sides of the stack to the metal casing as a dissipator; and a closure for said casing opening located opposite said insulating member and attachable after the solidification of said insulating filler. 15
2. A high duty electrical condenser of the stack-sheet type, which comprises a stack of serially-connected sections of interleaved sheets of dielectric and metal foils; an enclosing casing therefor having a metal wall of substantial heat-dissipating surface and with which the foils of a section of said stack are electrically and thermally in good connection; each section of said stack comprising sheets of dielectric and metal foils, and adjacent sections being insulated from one another at their faces but electrically and thermally connected together in series via said foils; a circuit terminal of high thermal conductivity in good thermal and electrical connection with the foils of a section of the stack which is substantially remote from said stack-section connected to a metal casing-wall, said terminal projecting to the exterior of the casing; and an independent metal heat-dissipator of substantial dissipating surface located outside the stack-casing, mounted on and thermally connected with the outwardly projecting portion of said circuit terminal, and extending radially substantial distances from said terminal, said metal heat-dissipator being spaced electrically closer than said terminal, from the stack-foils connected to said casing, whereby the heat-dissipator is an electrode of a protective spark gap for the stack. 40
3. A high duty electrical condenser construction comprising a condenser stack and a metal casing therefor with which said stack is connected as a low potential terminal, at least one end of said stack being in heat-conducting relation with a wall of said casing; said casing being formed with an opening and provided with an insulator closing said opening, said stack being provided with a high potential terminal extending thru said insulator to the outside of the metal casing; and a metal member outside the casing and mechanical- 45
- ly supported by and electrically and thermally connected with said high potential terminal; said metal member extending laterally from said high potential terminal and over said insulator, mechanically protecting the insulator and having a large heat-radiating surface; and said metal member being spaced from the metal casing to constitute a static shield for the insulator and a protective spark gap for the condenser elements. 50
4. In an electrical condenser comprising a stack of serially-connected sections of sheets, the combination with a metal casing for said stack and having an outlet opening; an insulating member substantially covering said outlet opening and having a passage for a stack terminal; a stack terminal projecting from one electrical end of the stack through said insulating member; 55 a metal member mounted on the casing and electrically connected with the other electrical end of the stack; and a second metal member mounted on said terminal in thermal and electrical conducting relation therewith extending over said insulating member as a protecting shield therefor, and spaced from said first metal member to constitute an electrode of a spark-gap with said first metal member in shunt to said stack. 60
5. In an electrical condenser, a casing including insulation; a stack therein comprising serially-connected sections of sheets; a solid metal stud terminal projecting from said stack through said insulation; and a solid metal member supported on and in conducting relation with said stud and beyond said insulation and outside said casing, and spaced from said casing; said metal member having all its surfaces exposed to the exterior atmosphere save those in conducting relation with said stud. 65
6. In an electrical condenser, a stack of serially-connected sections of sheets; a terminal projecting from one end of the stack; a casing for said stack having an opening through which said terminal projects; an electrically conducting member supported on the casing and electrically connected to the other electrical end of the stack; and a solid metal member mounted on said terminal outside the casing and in spaced relation to said electrically conducting member to constitute an electrode for a protective spark-gap with said electrically conducting member in shunt to said stack. 70
7. In an electrical condenser, a casing; a stack within said casing and comprising serially-connected sections of sheets; a terminal projecting through said casing and in thermally conducting relation with said stack; and a solid metal member mounted on said terminal outside the casing in thermally conducting relation with said terminal and having all its surfaces exposed to 75

the external atmosphere save those in thermally conducting relation with said terminal.

8. A high duty electrical condenser construction comprising a metal casing having a terminal opening, an insulating member closing said opening; condenser elements enclosed by said casing, connected thereto as one circuit terminal and as a heat dissipator; said condenser elements having another terminal constituting a heat conductor and extending out thru said casing opening and insulating member; a metal member outside the casing, supported by said extending terminal, electrically and thermally connected therewith, and extending laterally therefrom and over said insulating member; said metal member having large heat-dissipating surfaces and being spaced from said metal casing to constitute a protective spark gap between the opposite potential terminals of the condenser; said condenser elements of higher potential and the portions of the casing adjacent thereto being spaced from one another; and an insulating heat-conveying medium in the space between the condenser elements and the metal casing as a heat dissipator.

9. The combination with a high duty electrical condenser stack, of a metal casing therefor having its inner wall spaced from the lateral portion of the stack, at least one end of the stack being held under high mechanical compression against a wall of the metal casing, the stack being electrically and thermally connected via its said end with the metal casing as a low potential condenser terminal and a heat dissipator of large surface; said casing having an opening and a terminal extending from a high potential portion of said stack to and thru said casing opening; an insulating member closing the said opening and surrounding said high potential terminal; and a metal member outside the casing, supported by said high potential terminal, electrically and thermally connected therewith, and extending laterally therefrom and over said insulating member; said metal member having a substantial heat-dissipating surface to dissipate heat conducted by the high potential terminal from the stack thru the casing opening; the opposite casing opening being in communication with the interior space between the stack and the casing and permitting the introduction of molten insulating material into said space while the condenser is under said compression, to serve thereafter to conduct heat from the sides of the stack to the metal casing as a dissipator; and a closure for said casing opening opposite said insulating member and attachable after solidification of said insulating filler.

10. In an electrical condenser, a metal casing provided with heat-radiating ribs externally; a stack of serially-connected sections of sheets inside said casing; means for clamping the stack from end to end within

65 the casing; an insulating top cover plate for

the casing; a terminal lead projecting through said insulating cover plate to the outside of the casing; and a metal member secured to said terminal lead outside the casing, and extending over, near to but separated from said insulating top cover plate to protect the same, said metal member being arranged in conductive relation with said terminal lead to co-operate with said casing ribs in conveying heat from the internal stack to the external atmosphere.

11. The combination with a high duty electrical condenser, of a metal casing therefor having its inner wall spaced therefrom, and having two openings at opposite portions thereof; a terminal extending from a high potential portion of said condenser to and thru one of said casing openings; an insulating member closing said opening and surrounding said high potential terminal; the high potential portions of the stack being located near said insulating member, and a low potential end of the stack being in heat-conducting and electrically conducting relation with a wall of the metal casing as a heat dissipator and condenser terminal; a metal member located outside the casing, supported by said high potential terminal, electrically and thermally connected thereto, and extending laterally therefrom and over said insulating member; said metal member having a substantial heat dissipating surface to dissipate heat conducted by the high potential terminal from the stack thru the casing opening; the opposite casing opening being in communication with the interior space between the stack and the casing and permitting the introduction of molten insulating material into said space while the condenser is under said compression, to serve thereafter to conduct heat from the sides of the stack to the metal casing as a dissipator; and a closure for said casing opening opposite said insulating member and attachable after solidification of said insulating filler.

12. In an electrical condenser, a metal casing having ribs thereon for increasing the heat-radiation and conduction, a spring plate, and a pressure plate mounted in said casing at one end, a condenser stack comprising sections connected in series resting upon said plates and having its adjacent end electrically connected to said plates and the casing, the casing constituting a terminal therefor, said casing tapering upwardly and outwardly from one end of the stack towards the high potential end of the stack, a pressure member resting upon the high potential end of the stack and having a threaded stud projecting vertically therefrom, an insulating member surrounding said stud above said high potential pressure plate and having a plurality of concentric ribs thereon for increasing the creepage distance, a metal clamping collar overlapping said insulating

- member, screws arranged around said collar and threaded into the casing for clamping the insulating member against said high potential pressure member, a metal disc secured in conductive relation to said stud and spaced from said collar providing a spark gap therewith, and an embedment of solid holosteric insulating material packed around the high potential end of the stack, a space 5 being provided between the lower end of the casing and the spring plate to allow expansion of the insulating material, the bottom of the casing having an opening adjacent said space through which the casing 10 may be filled with the insulating material, and means for closing said opening.
13. In an electrical condenser, a metal casing, condenser elements within said casing and electrically connected thereto, an insulating bushing mounted on said casing, a high potential terminal connected to said elements and extending through said bushing, and means for preventing electrical losses in said bushing and mounted above 15 the same on said terminal, said means also constituting an electrode of a protective spark gap.
14. A high potential electrical condenser comprising condenser elements and a metal casing therefor to which said elements are connected as a low potential terminal; said casing being formed with an opening and provided with an insulator closing said opening; said condenser elements being provided with a high potential terminal extending outside the condenser casing thru the insulator; and a metal member located outside the casing and mechanically supported by and electrically connected with said high 20 potential terminal; said external metal member extending laterally from said high potential terminal and over said insulator and closer (in a line outside said insulator) to the nearest portion of the metal casing 25 than the shortest distance via the insulator between the high and low potential terminals of the condenser, whereby said metal member serves as a static shield for said insulator and as an electrode of a protective spark gap for the stack.
15. A high duty electrical condenser of the stack-sheet type, which comprises a stack of serially-connected sections of interleaved sheets of dielectric and metal foils; an enclosing casing therefor having a metal wall of substantial heat-dissipating surface and with which the foils of a section of said stack are electrically and thermally in good connection; the sides of said stack 30 being spaced from the enclosing casing; each section of said stack comprising sheets of mica and metal foils, adjacent sections being insulated from one another at their faces but electrically and thermally connected together in series via portions of said foils projecting from the stack into said space around the stack-sides; a circuit terminal in good thermal and electrical connection with the foils of a section of said stack which is substantially remote from 35 said stack-section which is connected to the metal casing-wall, said terminal projecting to the exterior of the stack-casing; a heat-conducting insulating filler in said space and surrounding said terminal and conducting heat from the stack foils to said metal casing-wall and to said circuit terminal; and an independent metal heat dissipator of substantial radiating surface and located outside the stack-casing, mounted on and 40 thermally and electrically connected with the outwardly projecting portion of said circuit terminal and extending radially substantial distances from said terminal, said radially extending portion being spaced 45 electrically closer to the metal casing than the shortest distance thru the insulating filler between the casing and the terminal.
16. A metal-encased stack condenser wherein the casing has an opening for a lead from one stack terminal and itself is electrically and thermally connected to another stack terminal of different potential; a casing-cover of insulating material over said opening and around said lead; safety 50 means electrostatically protecting said stack and the insulating material of said cover, said means comprising a metal member located outside the metal casing, supported by and thermally and electrically connected to 55 said terminal lead and extending radially and annularly therefrom over said casing opening and insulating cover, and spaced from the metal of the casing around the opening therein to constitute it an electrode 60 of a safety spark gap for said stack and a static shield for the insulating material of said cover.
17. A metal-encased stack condenser wherein the casing has an opening for a lead from one stack terminal and itself is electrically and thermally connected to another stack terminal of different potential; a cover of insulating material over the casing opening and secured to the casing 65 around the opening and projecting outwardly of the opening; and an annular metal projecting shield connected to said lead and located outside the casing beyond the insulating cover but spaced from the metal of the casing so as to be an electrode 70 of a safety spark gap in shunt to the stack and a static shield for the insulating material of the cover, said shield serving also to protect said cover mechanically and also 75 having a large surface dissipating heat conducted from the stack by said terminal lead.
18. A metal-encased stack condenser wherein the casing has an opening for the extension of a lead from one stack terminal 80

- and itself is connected to another stack terminal of opposite potential and wherein an insulating member covers said opening; a rigid construction including a stack terminal lead structure clamped with the stack inside the casing and projecting thru the casing opening and cover; and an annular metal static shield for the insulating cover, said shield being supported on said terminal lead
- 10 outside the casing and extending in proximity to the metal of the casing to constitute it an electrode of a safety spark gap shunting the stack.
- 15 19. An electrical condenser comprising a stack of serially connected sections, a metal enclosing casing therefor comprising a cover of insulating material thru which a high potential terminal of the stack projects, said projecting terminal carrying a conducting member extending radially in substantially all directions from said terminal and having its periphery spaced from the metal of the casing constituting it an electrode of a protective spark gap for the stack, said conducting member also constituting a static shield for the insulating material of the cover.
- 20 20. A metal-encased electrical stack condenser wherein the casing has an opening for the extension of a lead from one terminal of the stack and itself is connected to another terminal of the stack of different potential, and a radially extending annular projection over the casing opening; of that portion of the terminal lead which is located outside the casing, said projection having a large heat dissipating surface and being spaced from the rim of the enclosing opening to constitute it an electrode of a protecting spark gap of which the other electrode is said casing.
- 25 21. An electrical condenser comprising a stack of serially connected sections, a metal enclosing casing therefor comprising a cover of insulating material thru which a high potential terminal of the stack projects, said stack and casing being spaced from one another to receive a fusible insulating filler; and said high potential terminal carrying a conducting member thermally connected thereto and extending radially in substantially all directions therefrom thereby constituting a static shield for said insulating cover, the large heat dissipating surface of said shield serving to facilitate solidification of the insulating filler adjacent the high potential parts of the condenser with which said shield is in thermal communication via the high potential terminal.
- 30 22. A metal encased stack condenser wherein the casing has an opening for a lead from one terminal of the stack and itself is electrically and thermally connected to another stack terminal of different potential; a cover of insulating material for said casing opening, the metal of the casing extending around the insulating cover and assisting in supporting the cover in place, and the insulating cover projecting outside the casing and perforated to permit projection of said terminal lead; and a safety spark gap electrode and static shield consisting of an annular extending member of conducting material mounted on the projecting portion of said terminal lead outside the casing and beyond the outwardly projecting insulating cover and extending radially from the projecting terminal into protecting spark gap proximity to the metal of the casing around the casing opening and insulating cover.
